United States Patent Office.

LEWIS G. HOFFMAN, OF ALBANY, NEW YORK.

Letters Patent No. 79,760, dated July 7, 1868.

IMPROVED PARLOR ICE-CREEPER.

The Schedule referred to in these Letters Patent and making part of the same.

TO ALL WHOM IT MAY CONCERN:

Be it known that I, LEWIS G. HOFFMAN, of the city and county of Albany, and State of New York, have invented a new and useful Improvement in "Ice-Creepers;" and I do hereby declare that the following is a full and exact description of the same, reference being had to the accompanying drawing, and to the letters marked thereon, forming a part of my specification.

My improvement consists in preparing an ice-creeper with a detachable spur, which may be easily removed on coming into the house, to avoid injuring oil-cloths, carpets, &c., and also to avoid denting or marking the floor.

My parlor ice-creeper consists substantially of a plate, to be permanently attached to the boot or shoe of a detachable spur, and of the means by which said spur may be attached to or detached from said permanent plate.

In the drawings—

Figure 1 represents the heel of the boot or shoe, with the plate A permanently attached.

Figure 2 represents a section of the heel of the boot or shoe, and of the plate A, showing the manner of attaching the plate to the boot or shoe. It also represents a section of the detachable spur B, and one mode of attaching the same to the plate A.

Figure 3 shows the plate A and the detachable spur B in position, of which fig. 2 shows a vertical section.

Figure 4 shows the plate A without the spur B, representing the slot *c c* and the circular opening *a*, making together the opening *c a c*, for the purpose of receiving the spur, or the wings thereof, through the plate A, to be fastened thereto by turning the spur, as indicated by the dotted lines in fig. 4.

Figure 5 represents a vertical section of the plate A and spur B, to illustrate another mode of attaching the spur to the plate by means of the key *f*, as shown in Figure 6.

By this latter method the plate A, as represented in fig. 1, admits the spur through an opening therein, to pass a shank, *d*, as seen in fig. 5, to the bottom of the heel of the boot or shoe, and makes the spur fast to the plate A, by means of passing a key, as seen in fig. 6, through an opening or hole in the shank of the spur, as shown in fig. 5, *f*.

Having thus fully described my invention, I will now proceed to set forth the extent and nature of my claim.

I do not claim any particular mode of attaching the ice-spur to the plate A, or to the heel of the boot or shoe; but

What I do claim as my invention, and desire to secure by Letters Patent, is—

A detachable spur for an ice-creeper, in combination with the plate A, or its equivalent, substantially in the manner and for the purpose above described.
